UNITED STATES PATENT OFFICE.

FRANK BILLINGS, OF CLEVELAND, OHIO.

CONVEYER.

1,212,890.

Specification of Letters Patent. Patented Jan. 16, 1917.

Application filed March 19, 1913. Serial No. 755,274.

To all whom it may concern:

Be it known that I, FRANK BILLINGS, a citizen of the United States, residing at Cleveland, in the county of Cuyahoga and State of Ohio, have invented a certain new and useful Improvement in Conveyers, of which the following is a full, clear, and exact description.

This invention relates to conveyers or conveying apparatus adapted particularly for use in mines in association with a mining and loading machine, such for example as disclosed in my pending application for mining and loading apparatus, Serial No. 15 538,408, filed Jan. 10th, 1910.

The main objects of the present invention are as follows: First,—to provide an efficient, strong and durable conveyer which may be placed at the rear or discharge end 10 of a mining or loading machine, so as to receive material therefrom, and which will convey the material rearwardly a suitable distance to enable the material to be loaded into cars in the most economical manner. Second,—to provide a conveyer which is supported at its forward end preferably by means of a track, and which extends rearwardly from the truck a sufficient distance, and at a suitable height above the mine track 20 to enable a number of empty cars to be simultaneously run underneath the rearwardly projecting part, so that the cars can be loaded very rapidly and handled in a very economical manner, and specifically, in order that after a car under the discharge end of this conveyer is loaded, it may be taken away and the empty car, in advance of the one just loaded, can be moved rearwardly to the discharge end of the conveyer, 30 and so on, until the entire series of cars previously underneath the conveyer are loaded. Third,—to provide a conveyer which has the characteristics above stated, as to length and manner of being supported, and which can be conveyed without difficulty about the 40 curves of the mine tracks.

The above objects are accomplished in an effective manner by the present embodiment of my invention, wherein the conveyer comprises a collapsible or telescopic frame which is supported at its forward end as a cantilever beam by means of a truck, the whole, when extended and in use, being quite rigid and self sustaining.

In the drawings illustrating the above referred to embodiment of my invention, Fig.

ure 1 is a side elevation of the conveyer arranged at the rear of and connected to the rear end of a mining and loading machine, here shown conventionally; Fig. 2 is a top plan view of the conveyer embodying my invention, the belt being removed, parts being broken away, and the whole being shown on an enlarged scale with respect to the scale of Fig. 1; Fig. 3 is a side view of the frame and belt of the conveyer with the conveyer collapsed or the different sections of the conveyer frame telescoped together; Fig. 4 is a side elevation of the rear portion of the conveyer extended, parts being broken away for the sake of illustrating details of construction; Fig. 5 is a central sectional view of the forward end of the conveyer; Fig. 6 is a transverse vertical sectional view substantially along the line 6—6 of Fig. 1, 75 looking forwardly; Fig. 7 is a transverse vertical sectional view substantially along the irregular line 7—7 of Fig. 3, looking forwardly; and Fig. 8 is a horizontal sectional view of a portion of the conveyer at 80 the forward end thereof, this section being taken substantially along the line 8—8 of Fig. 1.

As before stated, the conveyer is preferably employed in connection with a mining and loading machine. This machine, a part of which is shown at 10, in conventional manner, forms no part of the present invention and it is believed to be sufficient to state merely that the machine includes a digging or scraping member which is adapted to move material rearwardly to a conveyer, shown in outline at 10^a, which moves the material upwardly and rearwardly from the forward end of the machine. The conveyer forming the subject matter of the present invention is with respect to the conveyer of the mining and loading machine 10, an auxiliary conveyer, and is arranged with its forward end below the discharge end of the 100 conveyer of the machine 10, so as to receive the material from the latter and to convey the same rearwardly.

The conveyer of the present invention is supported wholly at its forward end upon a truck 11 adapted to run upon the tracks of the mine. This truck, it will be observed, is connected to the rear end of the frame of the mining and loading machine 10 which thus serves to counterbalance the auxiliary 110 conveyer. Swiveled to the truck by means of a king bolt 12, is a turn table 13, which is

supported from the truck by suitable rollers, including rear rollers 14, and a forward roller 15 which engages the flanges of a suitable arc-shaped trackway or guide 16. Supported at the forward end of this turn table 5 in suitable bearings 17, is a shaft 18 provided with a drum or pulley 19 which drives the endless belt 20 of the conveyer. This shaft is driven by an engine or motor 20^a which is supported on the turn table 13, and which is supported on the turn table 13, and 10 is suitably geared to the shaft. The shaft 18 also constitutes a pivotal bearing member for the forward end of the conveyer frame, as will be hereinafter described. At the rear end of the turn table and a short 15 distance to the rear of the front pivotal support of the conveyer frame is a vertically adjustable support 21 for the conveyer, in the nature of a fulcrum. This includes a hand wheel and a suitable threaded shaft, by 20 means of which the rear end of the conveyer can be raised or lowered, with respect to the trackway, the forward end of the conveyer thence turning slightly about the axis of the front driving shaft 18.

25 By reference particularly to Fig. 1, it will be seen that the conveyer frame is supported from its front end in a manner just described, so as to constitute in effect a cantaliver beam, which extends rearwardly in a substantially horizontal direction, and is unsupported, except at the front end as described. This frame or cantaliver beam is collapsible, and preferably is composed of 30 a number of telescoping sections, in this case three in number, designated A, B and C. When the frame is extended, as shown in Fig. 1, it has sufficient length and the portion at the rear of the front truck 11 is supported a sufficient distance above the track to enable a number of mine cars 22 to be run underneath the conveyer. As shown in Fig. 1, three cars are wholly beneath the conveyer, and a fourth is below the discharge end of the conveyer or the rearmost 40 section A. It will be understood that in the use of this apparatus, the rearmost of the group of empty cars will be loaded, and thence the loaded car will be taken away 45 and the group yet unloaded will be moved forwardly until the next adjacent car, or the one next to the car just loaded, is in position to be loaded. Thence the remaining cars will be successively loaded, after which 50 another group of empty cars will be run under the conveyer and loaded in the manner stated. In this manner, the cars can be loaded with a minimum loss of time in moving backwardly and forwardly the cars from 55 and to the conveyer.

60 Considering now the details of construction of the conveyer, and especially of the frame, it will be seen that the rearmost section A, (see particularly Fig. 7) is provided 65 with a frame comprising two substantially

horizontal I-beams 23, flanking the belt and as close to the edges thereof as is practicable, and a plate 24 which joins the two beams, and is located between the upper and lower parts or sections of the belt, so as to form 70 a shield for the lower forwardly traveling part of the belt. On the upper flange of each beam is an angle 25, with its upstanding leg in the center plane of the I-beam, the other leg extending outwardly therefrom, and forming with the adjacent parts 75 of the apparatus, a runway for a chain 26, whose function will be explained later.

At the forward end of each I-beam 23, a portion of the beam flange not occupied by 80 the previously mentioned angle 25 is bent downward to form an inclined plane, the function of which will be presently explained. This section A has a plurality of sets of rollers 28, each set including a central 85 horizontal roller and side inclined rollers which are arranged to turn on fixed axes and support the upper part or rearwardly traveling part of the conveyer belt 20. At the rear end of the section A is a roller or 90 drum 29 about which the belt 20 runs or travels.

The middle section B of the frame comprises a pair of girders 30, which are located with respect to the belt, as are the I-beams 95 23 of the rearward section, but which are spaced a sufficient distance apart to enable the passage of the I-beams 23 of the rear section between them. These girders which are in the form of channels extend slightly 100 below the bottom plane of the I-beams 23, and the lower flanges are joined by a thin plate 31 arranged in a plane below the plate 24, and overlapping the same. These two plates, together with the corresponding plate 105 31 of the forward section C constitute a shield for the lower part of the belt, and prevent material dropping from the upper part of the belt down on to the lower part.

On the inner side of each girder 30, near 110 its rear end, are two rollers 32 arranged a short distance apart, and mounted for free rotation about the axis of supporting pins or studs. These rollers are of the proper size, and are properly located to fit into the 115 space between the outwardly extending flanges of the I-beams of the rearward section A of the frame, so that the I-beams are supported by these rollers with sufficient clearance, however, to permit the I-beams to 120 move freely backward and forward over the rollers.

At the rear ends of the two girders 30 are a pair of chain sheaves 33, which are adapted to be engaged by the chains 26 125 previously referred to, and in a manner to be described, and below the rear end of the frame of the middle section B is a belt supporting roller 34, which supports the lower part of the belt.

The upper part of the belt is supported on this section of the frame by means of two sets of rollers 35 and 36, (see Fig. 2.) The front or forward set of rollers are supported in fixed relationship with respect to the girders or frame of this section, but the rear set are supported in a vertically swinging frame or bail 37, which is pivotally supported at its rear end upon the top flanges of the two side girders, so that the said bail or frame and the rollers supported by it may swing upwardly when engaged by the downwardly inclined or tapered forward ends of the I-beams 23 of the rear section A so that said I-beams or the frame of the rearmost section may be moved forwardly under said rollers, while the frame is being collapsed.

To the back of each channel 30 are secured two angles 39 and 40, which are secured to the channels so that the space between their outstanding legs is less than the depth of the channel. The outstanding flange of the upper pair of angles of the two girders constitute a track or guideway for rollers to be hereinafter described, and the outstanding legs of the lower angles are drilled at regular intervals substantially throughout the length of the angles, for a purpose to be described.

The frame of the forward section C of the conveyer consists of two built-up girders 42, joined by a plate 43 which is not seen in Fig. 7, but is shown in Figs. 2 and 4. This plate is below the plane of the plate 31, and overlaps the same, as before stated, so as to form with the plates of the middle and rear section, a continuous telescopic shield for the lower part of the belt, as before described. The rear part of the girders or of the frame of the forward section C is substantially horizontal, as shown in Fig. 1 the horizontal portion extending to a knuckle near the forward end of the section, and thence the frame inclines downwardly to the forward end of the conveyer. The forward ends of the frame terminate in trunnions which engage in the manner previously referred to, with the drive shaft 18. The knuckle or bend is just above the adjustable vertical support 21, which as before stated, is at the rear end of the turn table 13.

Secured to the rear end of the frame of section C are a pair of chain anchors and take-ups 45, to which the forward ends of the chains 26, previously referred to, are connected. These chains extend rearwardly from these chain anchors and take-ups, and pass about the sheaves 33, at the rear end of section B, and thence extend forwardly to fixed points 46, on the frame of the rear section A. These chains, it may be here stated, are employed in telescoping or collapsing the frame, and also in extending the frame.

The section C of the frame has two sets of rollers 47 and 48, similar to the sets 35 and 36 of the middle section B, and adapted to support the upper part of the belt. The forward set 47 are in fixed position, but the rear set 48, are like the set 36 of the middle section, carried by a pivoted frame or bail 49, pivotally secured at its rear ends to the rear portion of the frame section C, so that said frame and rollers carried thereby, may be swung upwardly when engaged by the forward end of the middle frame section B, when the entire frame is being collapsed. At the lower rear end of the frame section C is a roller 51, which supports the lower part of the belt. See particularly Fig. 4.

It will be observed that the girders 42 are provided near their rear ends with rollers 52, which are mounted or supported on the inner sides of the girders, and are engaged by the outstanding flanges of the upper angles 39, secured to the outer sides of the girders of the middle frame section. It will be seen also that the frame section C is provided at its lower rear end with a transverse shaft 53, rotatably supported in suitable bearings, and provided near the inner sides or faces of the two girders 42 with sprockets 54 or toothed wheels, having teeth which engage in the openings in the outstanding flanges of the lower angles 40, secured to the outer side of the girders 30 of the middle section C. This shaft 53 extends outwardly beyond one side of the frame, the outwardly extending part being provided with a ratchet wheel 55, which is adapted to be engaged by a pivotal pawl 56 (see Fig. 2), and at its extreme outer end, the shaft 53 is provided with a sprocket wheel 57, (see Figs. 2 and 7).

The pawl and ratchet, above referred to, normally prevent any backslapping of the frame sections, and consequent loosening of the belt, but when it is desired to collapse the frame, or to extend the same, the pawl will be thrown out of engagement with the ratchet. The frame can be extended by rotating the shaft 53 at the rear end of the frame section C. This shaft can be rotated by a sprocket chain 58, which extends about the sprocket 57 on said shaft 53, and about a sprocket 59 at one end of the driving shaft 18. This sprocket wheel 59 is normally loose on the shaft, but can be clutched thereto when desired, by a suitable friction clutch 60.

The rotation of the shaft 53 and of the toothed wheels 54 cause the middle section B, to be moved outwardly with respect to the forward section C, by reason of the engagement of the teeth of the toothed wheels 54 in the openings provided in the angles carried by the girders of said middle section. The end section A is likewise moved outwardly by reason of the fact that the sec-

70

tions A and B are connected in a manner previously described, by means of the chains 26. This same mechanism could be used for collapsing the frame, providing the power plant which drives the belt comprises a reversing motor. I prefer, however, to use a non-reversing motor.

To collapse the frame, the pawl will, as before, be out of engagement with the ratchet, and the outermost section A and middle section B can be pulled inwardly, by a suitable rope 61, extending about a capstan head 62, on the opposite end of the driving shaft 18 from that provided with the sprocket 59, and about a sheave 63, at the rear end of the rearmost section A.

When the frame is being extended, the sprockets 54 on the shaft 53, move the middle section outwardly and the chains 26 cause the outermost section to be moved outwardly at twice the rate of speed of the middle section. When the frame is being collapsed, by pulling inward the section A, the same chains 26 cause the middle section to be moved inwardly, at one half the rate of speed that the outermost section is moved.

When the frame is being collapsed, the pivotally mounted sets of rollers 36 and 48 are swung upwardly, out of the path of movement of the oncoming ends of the outer section A and the middle section B respectively. When the conveyer frame is collapsed, the belt is not removed therefrom, but the outermost portion of the belt may be folded or swung over the top of the conveyer frame, in the manner shown in Fig. 3.

The conveyer is provided at its forward end with a hopper 65 having an open bottom, a closed lower end, and inclined sides 40 which extend along the forward inclined part of the frame, and preferably a short distance along the horizontal part, as shown. When the conveyer is in operative position at the rear of the mining and loading machine 10, material will be discharged from the rear end of the conveyer machine 10 into the hopper and will thence be picked up by the belt 20, and conveyed rearwardly to the discharge end of the auxiliary conveyer, 50 where the material will be discharged into cars, as previously described.

Having thus described my invention, what I claim is:

1. In a conveying apparatus, a truck, a turn table swiveled to said truck, a conveyer supported by said turn table, said conveyer comprising a frame pivotally connected at its forward end to the turn table, said frame inclining upwardly from the pivoted end 55 and thence extending substantially horizontally, the horizontally extending part being composed of plurality of telescopic sec-

tions, and means for maintaining the free end of the conveyer at a desired elevation, comprising an adjustable fulcrum between the forward portion of the conveyer and said turn table.

2. A conveyer comprising a conveyer frame, and an endless belt carried thereby, the frame being composed of a plurality of telescopic sections, rollers carried by said sections for supporting the belt, the said rollers of one section being mounted for movement vertically so as to be movable out of the path of movement of the next adjacent section when the frame is being collapsed.

3. Conveying apparatus comprising a collapsible frame including a pair of telescopic sections, a belt supported thereby, the two sections having rollers which support the belt, a support for a roller of one section, said support being movably connected to the said section so that the roller carried by the support may move out of the path of movement of the other section when the frame is collapsed.

4. A conveying apparatus comprising a collapsible frame, a belt carried thereby, said frame comprising a plurality of telescopic sections having belt supporting rollers, movable frames carrying part of said rollers, and connected to the sections of the conveyer frame whereby the rollers may be elevated when the conveyer frame is being collapsed.

5. A conveying apparatus comprising a collapsible frame, and a belt carried thereby, said frame comprising a pair of telescopic sections, one section having a roller for supporting a part of the belt, a pivoted frame supporting the roller, said frame having a portion in the path of movement of the other section so that the said roller will be elevated when the frame is collapsed.

6. In a conveyer, a collapsible conveyer frame composed of a plurality of telescopic sections including a pair of movable sections and a relatively fixed section, means carried by the relatively fixed section and operatively connected to the adjacent movable section for shifting said movable section, and means connecting said movable section with another movable section for causing said second movable section to be moved simultaneously with the first movable section, but at a different rate of speed.

In testimony whereof, I hereinunto affix my signature in the presence of two witnesses.

FRANK BILLINGS.

Witnesses:
